his Attorney.

Patented May 24, 1927.

1,629,591

UNITED STATES PATENT OFFICE.

FREDRICK B. SOMERSTEIN, OF JACKSONVILLE, FLORIDA.

BASE FOR TIME-CONTROLLED SWITCHES.

Application filed May 4, 1925. Serial No. 27,721.

My invention consists of a new and simple time switch base and has for its main and particular object to provide a base which, when installed in an electric circuit, may be used in combination with a clock having a spring actuated metal lever arm for closing or breaking the circuit at a predetermined time.

A further object is to so construct this device that, when two of same are connected in series in an electric circuit, one of said devices will close the circuit at a predetermined time and the second device, which has reversed contacts, will break the circuit at another predetermined time.

A still further object is to provide a time switch base simple in construction, of few parts, easy and inexpensive to manufacture and install and in which an ordinary alarm clock may be used as the time element.

These and various other objects and advantages will be clearly understood from the following description and from the accompanying drawing of a preferred embodiment of my invention but it will be readily seen that various modifications might be made without departing from the scope of the invention.

Fig. 1 is a front elevation of my invention.

Fig. 2 is a rear elevation of same.

Fig. 3 is a cross-sectional side elevation, taken on line 3—3 on Fig. 1.

Fig. 4 is a diagram showing a certain application of my invention, drawn to a somewhat smaller scale.

In a general way, the device may be described as consisting of an annular ring, made of insulating material, to which an alarm clock is attached and in which contact points, having terminals to receive wires, are embedded and a contact arm attached to the alarm winding stem of the clock.

Referring now to Figs. 1, 2 and 3, 1 is an ordinary alarm clock from which the alarm hammer and gong have been removed. 2 is the winding stem of the alarm spring and 3 is a metal contact arm rigidly attached to the winding stem 2. The clock is attached, by means of the slotted lugs 4, to an annular ring 5 in which are embedded the studs 6 which engage in the slots in these lugs. The annular ring 5, which is cast of any suitable insulating material, is provided with two metal contact points 7 and 8.

The contact point 7 is embedded in the ring 5 with one end located on the face of

the ring and the other end extending downwardly and rearwardly, ending in a tubular terminal 9 extending to the interior of the ring and to which an electric wire may be attached.

The contact point 8 is also embedded in the ring 5 but with the outer end slightly above the face of the ring so that contact may be made on the under side of this portion. The other end extends downwardly and rearwardly and ends in a tubular terminal 10, likewise extending to the interior of the ring. Both contact points are provided with tongues or anchors, 11 and 12, to provide additional rigidity. This construction is plainly shown in Figs. 2 and 3.

The spring of the alarm mechanism is wound up before the contact arm is attached to the winding stem and this arm extends outwardly, through a slot in the clock case, and engages at all times one, or both, of the contact points.

The device operates in the following manner:

The alarm mechanism is set, in the usual manner, so that it will operate at any desired time and the contact arm 3 is raised to its upper position. When the time arrives, at which the alarm mechanism has been set to operate, the contact arm, actuated by the alarm spring, flies downward, making contact with both points 7 and 8 and closing the circuit. The movement of the contact arm is limited by a slot in the clock case and is sufficiently rapid to prevent arcing. It will be noted that when the contact arm is raised to set the mechanism, the alarm spring is rewound. The device is made operative or inoperative at will by means of the release lever 13 which is a regular part of an alarm clock.

It will be noted that the means for fastening the clock 1 to the ring 5 are such that a slight twist will immediately disengage the clock for any desired purpose, such as winding, setting, etc.

The above description has shown the device as used to close an electric circuit. When it is desired to employ the device for breaking the circuit, a contact point 8 is placed in the upper position and a contact point 7 is placed in the lower position, as shown on B in Fig. 4. In this case, when the contact arm 3 is in its upper position, it makes contact with both points and, when the predetermined time arrives, it flies

downward to its lower position and breaks the circuit.

Referring now to Fig. 4, A represents the device shown in Figs. 1, 2 and 3 while B 5 represents a similar device with the contact points reversed, as above described. When it is desired to automatically close the circuit at a predetermined time and break the circuit at another predetermined time, devices A and B are installed in the circuit, as 10 plainly shown.

This installation operates as follows: The alarm mechanism of the device A is set, in the usual manner, to operate at the time it 15 is desired to close the circuit and the contact arm raised to its upper position, which breaks the circuit. The alarm mechanism of the device B is set, in the usual manner, to operate at the time it is desired to open 20 the circuit and the contact arm raised to its upper position, which closes the circuit at this point. When the first predetermined time arrives, the alarm mechanism of the device A operates and the contact arm flies 25 to its lower position, closing the circuit and allowing the current to flow through the

wire 14 until the time arrives at which the device B is set to operate. Then the alarm mechanism of the device B operates, the contact arm flies to its lower position and 30 breaks the circuit.

Having thus described my invention, what I claim as new and wish to protect by Letters Patent is—

An annular apertured member composed 35 of insulation material mounted on a conventional alarm clock, said alarm clock being provided with oppositely disposed attaching pins, said member having oppositely disposed slotted attaching lugs adapted to engage 40 said pins, stationary contacts on said ring, adapted to be bridged by a bridging contact, the latter being mounted on the alarm arbor of said clock, each of said contacts comprising a tubular current conductor 45 attaching portion, a contact portion and an anchoring portion, said anchoring portion adapted to be embedded in said ring.

Signed at Jacksonville, in the county of Duval and State of Florida, this 29th day 50 of April 1925.

FREDRICK B. SOMERSTEIN.
